Patented July 16, 1918.

UNITED STATES PATENT OFFICE.

ROBERT MIEHLE, OF CHICAGO, ILLINOIS.

MECHANISM FOR ADJUSTING PAPER UPON FEED-BOARDS.

1,273,081.

Specification of Letters Patent.

Patented July 16, 1918.

Application filed November 27, 1916. Serial No. 133,761.

To all whom it may concern:

Be it known that I, ROBERT MIEHLE, citizen of the United States, residing at Chicago, in the county of Cook and State of Illinois, have invented a certain new and useful Improvement in Mechanism for Adjusting Paper Upon Feed-Boards, of which the following is a full, clear, concise, and exact description.

10 My invention relates to feed boards such as are employed in connection with paper folding machines, printing presses, etc., and has for its object the provision of means for changing the position of sheets or lifts of 15 paper upon the feed boards.

In my invention I employ roller mechanism operating to impart or permit movement of a sheet or lift of paper longitudinally of the feed board, this roller mechanism desirably including a plurality of rollers having parallel axes of rotation that are at right angles to the general line of travel in which the paper is being fed. The sections of the feed board intervene between 25 the rollers and extend beyond the first and last rollers, the rollers preferably permanently projecting slightly above the stationary supporting surface of the feed board to have tractive engagement with the sheets 30 or lifts.

I will explain my invention more fully by reference to the accompanying drawing showing the preferred embodiment thereof and in which Figure 1 is a plan view of a 35 feed board equipped with my invention and shown in association with an impression cylinder of a printing press, parts being broken away; Fig. 2 is a view on line 2—2 of Fig. 1; Fig. 3 is a detail view of some 40 of the parts as they appear in Fig. 2 taken on the line 3—3 of Fig. 1; and Fig. 4 shows a detail of construction taken on the line 4—4 of Fig. 1.

Like parts are indicated by similar characters of reference throughout the different figures.

The drawing shows the association of a feed board equipped with my invention with a printing press (of which a printing cylinder 1 is shown in Figs. 1 and 2) but the invention is not to be limited to such association.

The front division 2 of the feed board is the feeding end thereof from which the 55 sheets of paper are delivered singly to be operated upon by the mechanism to which

they are to be fed such as a printing press. The rear division of the feed board is preferably made up of sections 2¹ that together support the lift of paper indicated at 3 in 60 Fig. 2, the sheets being led from the lift or pile of paper 3 to the front or feeding portion of the feed board. The forward division of the feed board is customarily hinged at 4. The lift supporting portion of 65 the feed board is mainly the rear division, a portion of the lift usually being also carried upon the rear part of the feed board division 2. The rear division of the feed board is equipped with rollers 5 that project sufficiently above the paper supporting surfaces of the feed board sections 2¹, which surfaces lie in the same plane with each other and with the balance of the board. The rear portion of the forward 70 feed board division 2 that takes part in supporting the lift is formed in sections 6, similar to sections 2¹, and is equipped with rollers 7 that project above the paper supporting surface of the feed board to the 75 same extent as the rollers 5. The rollers 5 and 7 are preferably limited in movement longitudinally of the feed board. While I 80 preferably form the feed board in sections 2¹ and 6 for the purpose of enabling the 85 rollers 5 to project above the paper supporting surface of the feed board, I do not wish to be limited to this arrangement for enabling the projection of the rollers above the feed board nor to the complete separation 90 of the sections 2¹ and 6 which I have illustrated for the purpose of accommodating 95 the rollers.

As illustrated, the rollers 5 and 7 are received in slots that extend clear across the feed board and which slots are due to the formation of the feed board in sections 2¹ and 6. To prevent the paper from working through these slots I provide peripheral grooves 8 or other spaces in the rollers 5 and 7 that subdivide the rollers into spaced apart paper supporting sections, and form the sections 2¹ and 6 with noses 9 or other continuations that enter said grooves or spaces. These grooves are sufficiently deep 105 to enable the ends of the noses or continuations 9 to be positioned within the circles of the rollers, the noses terminating slightly below the paper supporting surfaces of the feed board whereby they prevent the paper 110 from passing through the roller containing slots. Each groove 8 desirably receives a

nose 9 upon each side of the roller having such groove so that the entry of the paper into a slot at either side of the roller is guarded against. To prevent the sheets 5 from being caught in the rollers when the sheets are moved crosswise of the board, I round the roller sections at the ends thereof which are adjacent the grooves 8. All of the rollers 5 upon the rear division of the 10 feed board are preferably equipped with roller driving mechanism. The rollers 7 upon the front division of the board may be idle rollers or they may also be driven if preferred. The driving mechanism illustrated 15 comprises sprocket pinions 10 located upon one side of the feed board and fixed upon the adjacent ends of the shafts 11 that carry the rollers 5. An endless sprocket chain 12 passes over the tops of these pinions 20 and is maintained in engagement with the teeth of these pinions by means of the guard plate 13, this chain being maintained sufficiently taut by means of the idler sprocket 14 which may be adjusted up or down by 25 the bolt and slot anchorage 15 for the bearing 16 of the wheel 14. The end of one of the shafts 11 that carries a sprocket pinion 10 is desirably equipped with a hand crank 17, or any other means for furnishing power, 30 the shaft 11 selected for the attachment of the crank 17 thereto being desirably that upon which the rearmost roller 5 is mounted. The foremost roller 5 desirably also has a crank 18 or some other suitable means for 35 furnishing power connected therewith, the crank 18 being located on the side of the feed board which is opposite to that upon which the crank 17 is located. By means of either crank 17 or 18 the sprocket pinion 10 rigid with respect thereto may be turned 40 to cause the travel of the endless sprocket chain and the simultaneous and synchronous rotation of the rollers 5. As illustrated in Fig. 1, the rollers 7 are not equipped with 45 any driving pinions but in Fig. 2 the sprocket chain 12 is indicated by dotted lines 12¹ as being extended to have driving connection with the rollers 7 similar to its driving connection with the rollers 5.

50 To prevent any of the rollers 5 from being turned by the shaking of the machine or the action of the lift thereupon and thereby cause undesirable movement of the paper upon the same, I employ a suitable braking device, one form of braking device being 55 illustrated in Figs. 1 and 2 where I have shown a braking clamp 18 embracing the shaft 11 of the foremost roller 5 and comprising two jaws hinged together at one end of the clamp and coupled at the other end of the clamp by means of an adjusting wing screw 20. The braking clamp is so adjusted 60 that the shafts 11 may be turned notwithstanding the braking action of the clamp, 65 but which braking action is sufficient to pre-

vent the rollers from turning due to the shaking of the machine or the action of the lift of paper upon the rollers 5.

In the use of my device all of the sheets in the lift may be easily adjusted to the position of feeding, this being true even of the last remaining bottom sheet, and I do not therefore wish to limit myself to the adjustment of an entire lift of paper by means of my invention. 75

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. In mechanism for adjusting paper upon a feed board, the combination with a feed board for supporting the paper thereupon and having slots extending transversely of the board and through the paper supporting surface thereof; of rollers in said slots 85 projecting above the paper supporting surface of the feed board and divided into spaced apart paper engaging sections, the feed board having continuations extending into the spaces between the sections of the 90 rollers.

2. In mechanism for adjusting paper upon a feed board, the combination with a feed board for supporting the paper thereupon and having slots extending transversely of the board and through the paper supporting surface thereof; of rollers in said slots 100 projecting above the paper supporting surface of the feed board and divided into spaced apart paper engaging sections, the 105 ends of these roller sections being rounded, the feed board having continuations extending into the spaces between the sections of the rollers.

3. In mechanism for adjusting paper upon a feed board, the combination with a feed board for supporting the paper thereupon and having slots extending transversely of the board and through the paper supporting surface thereof; of rollers in said slots 110 projecting above the paper supporting surface of the feed board and divided into spaced apart paper engaging sections, the feed board having continuations in the form 115 of noses extending into the spaces between the sections of the rollers and which noses terminate beneath the paper supporting surface of the board. 120

4. In mechanism for adjusting paper upon a feed board, the combination with a feed board for supporting the paper thereupon and having slots extending transversely of the board and through the paper supporting surface thereof; of rollers in said slots 125 projecting above the paper supporting surface 130

of the feed board and divided into spaced apart paper engaging sections, the ends of these roller sections being rounded, the feed board having continuations in the form of 5 noses extending into the spaces between the sections of the rollers and which noses terminate beneath the paper supporting surface of the board.

5. In mechanism for adjusting paper upon 10 a feed board, the combination with a feed board for supporting the paper thereupon and having slots extending transversely of the board and through the paper supporting surface thereof; of rollers in said slots projecting above the paper supporting surface 15 of the feed board and divided into spaced apart paper engaging sections, the feed board having continuations in the form of noses extending into the spaces between the 20 sections of the rollers from opposite sides of the rollers and which noses terminate beneath the paper supporting surface of the board.

6. In mechanism for adjusting paper upon 25 a feed board, the combination with a feed board for supporting the paper thereupon and having slots extending transversely of the board and through the paper supporting surface thereof; of rollers in said slots 30 projecting above the paper supporting surface of the feed board and divided into spaced apart paper engaging sections, the ends of these roller sections being rounded,

the feed board having continuations in the form of noses extending into the spaces between the sections of the rollers from opposite sides of the rollers and which noses terminate beneath the paper supporting surface of the board. 35

7. In mechanism for adjusting paper upon 40 a feed board, the combination with a feed board for supporting the paper thereupon and having slots extending through the paper supporting surface thereof; of rollers projecting through said slots to engage the 45 paper upon the feed board; and operating mechanism common to a portion of the rollers and serving to operate the same simultaneously, the balance of the rollers being 50 idle.

8. In mechanism for adjusting paper upon 55 a feed board, the combination with a feed board for supporting the paper thereupon and having slots extending through the paper supporting surface thereof; of rollers projecting through said slots to engage the 60 paper upon the feed board, operating mechanism common to said rollers and serving to operate the same simultaneously; and a brake for normally holding the rollers from rotation.

In witness whereof, I hereunto subscribe my name this 20th day of November, A. D., 1916.

ROBERT MIEHLE.
